UNITED STATES PATENT OFFICE.

GLENN S. WILLIAMSON, OF NEW YORK, N. Y.

MECHANISM FOR UNITING PRINTING-PRESS WEBS AND THE LIKE.

1,217,252.

Specification of Letters Patent. Patented Feb. 27, 1917.

Application filed April 4, 1914. Serial No. 829,571.

To all whom it may concern:

Be it known that I, GLENN S. WILLIAMSON, a citizen of the United States, residing at New York, in the county of New York, 5 and State of New York, have invented new and useful Improvements in Mechanism for Uniting Printing-Press Webs and the like, of which the following is a full, clear, concise, and exact description, reference being 10 had to the accompanying drawing, forming a part of this specification.

This invention relates to an improved method of uniting or splicing pieces of paper and the like, and to means for carrying out such method.

The invention may in practice be advantageously employed in numerous instances. As an example, it has been used to great advantage in uniting or piecing together the 20 stubs of printing press rolls to form a new roll, which has enabled utilization of material previously treated as waste.

The various objects and advantages of the invention will hereinafter appear.

25 The accompanying drawings comprise schematic views exemplifying the method and certain of the preferred elements for carrying out said method and also views of a mechanical embodiment of such elements.

30 The means for carrying out the method may, of course, be embodied in other forms and may be provided with various additional advantageous features, such as those disclosed in an application of Gustave B. Reisbach, 35 Serial No. 831,063, filed April 10, 1914.

In the drawings,

Figure 1 shows schematically two pieces of material partially cut and partially united.

40 Fig. 2 shows schematically various elements preferably employed in cutting and uniting the material in the manner depicted in Fig. 1;

Fig. 3 is a general perspective view of a 45 mechanical embodiment of the means shown in Fig. 2;

Fig. 4 is a side elevation, partially in section, of the traveling device shown in Fig. 2.

50 Fig. 5 is a top plan view partially in section of the device shown in Fig. 4;

Fig. 6 is an enlarged detail view of a part of the device shown in Figs. 4 and 5;

Fig. 7 is a sectional view through the table and movable frame of Fig. 3; and,

55 Fig. 8 is a detail view of a part of the table, Fig. 3.

The method will be explained in connection with Fig. 1, which shows two pieces of material A and B, for brevity termed "webs". It consists in first overlapping the 60 ends of the two webs, preferably with their margins a and b in alinement. When so overlapped the webs are preferably firmly clamped to their support, as by means hereinafter set forth, and then severed on a common line x—y, preferably obliquely disposed or on a bias with respect to the webs. Thereupon the severed end a' of the upper web is displaced, leaving the cut edges of 65 both webs exposed and in abutting relation. The webs are then ready to be united and this is preferably accomplished by applying along the line x—y a sealing strip c to overlap and adhere to both webs. Of course, 70 the webs might be united in other ways than by the aforesaid overlapping sealing strip, but said strip is preferred. In this connection, also, it is preferred to employ for said strip a very thin rubber coated tissue paper or the like and to heat the same during application to effect adhesion thereof to the webs.

The aforesaid operations are in practice 75 preferably carried on simultaneously. That is to say the waste end of the upper web is displaced as the cutting progresses and the sealing strip is applied as the displacement of the waste material progresses.

By the method described the two webs or 80 other materials are securely united and the joint between the same is smooth and will only exceed the thickness of one web by that of the sealing strip, which may be very thin. In consequence, the webs when united may 85 be run through a press or other mechanism with little resistance at the line of connection and this resistance, as well as the strain on the joint, may be materially reduced by uniting the webs on an oblique line, as aforesaid.

100 Referring now to Fig. 2, the same shows a work supporting table 1 provided on its upper face with a groove 2 to receive the blade of the cutter, hereinafter specified. The table has overlapped thereon, across the 105 groove 2, the ends of two web rolls A and B. Clamping strips 3 are shown to clamp the overlapped ends against the table on opposite sides of the groove.

Fig. 2 also shows schematically a rotary cutter 4, a waste-displacing plow 5, a reel of sealing strip 6, and a heated pressure device 110

7 to apply the sealing strip to the webs. In practice, the aforesaid elements are preferably embodied in a unitary device mounted for movement across the table, as herein-
5 after set forth, and adapted to perform their respective functions automatically as the movement of said device progresses.

Referring now to Fig. 3, the apparatus as illustrated therein includes a table 1, as already described, a traveling device 10 carrying the above specified and other movable elements and a frame 11 extending across the table to support the traveling device 10 and also to carry the clamping strips 3 of
15 Fig. 2.

The frame 11 is preferably pivoted to the table 1 at one side thereof, as at 12, and counter-weighted whereby it may be readily raised to clear the table for arrangement of
20 the webs thereon and lowered to clamp the webs against the table. The device 10 travels back and forth longitudinally of the frame 11 and is moved into and out of operative relation with the work by movement of said frame. As shown, the device 10 is so arranged on the frame as to move to the right for cutting and sealing the webs when the frame is lowered to the table and after the cutting and sealing operation the frame is raised and the device 10 returned to the position shown.

First specifically considering the traveling device 10, the same is more fully illustrated in Figs. 4, 5 and 6. As best shown in Fig. 35 5, it includes an open supporting frame 15 provided at the right hand end with a transverse shaft 16 carrying supporting rollers 17 and 18 and at its opposite end with a transverse shaft 19 carrying supporting rollers 20 and 21. This frame 15 carries the aforesaid elements of Fig. 2 in the following relative positions—best illustrated in Figs. 4 and 6. The rotary cutter 4 and plow 5 are arranged at the base of said frame toward the rear end thereof, the former being shown in Fig. 4 and both being shown in Fig. 6. The pressure device 7 is connected to the rear of the frame while the roll of sealing strip is carried by a reel 22 on the upper side of the frame and is fed by suitable mechanism, hereinafter described, to a point between the cutter and the pressure device 7.

The traveling frame also carries a knife 23 for severing the sealing strip, said knife being interposed between the previously mentioned feeding mechanism and the pressure device 7. Still further, the frame carries a motor 24 for propelling the same along the aforesaid table frame 11 and by this propulsion supplying power to operate the rotary cutter 4 and aforesaid feeding mechanism.

More specifically considering the rotary cutter 4 the same is mounted upon a spindle
65

25 and is driven through pinions 26, 27 and 28 from a pinion 29; the latter, as best illustrated in Fig. 5, being fixed to a shaft 30 provided on the outside of the frame 15 with a driving pinion 31. The pinion 31, as will 70 be hereinafter more fully set forth, is adapted to mesh with a stationary rack on the table frame 11 and thus rotate the shaft 30 whenever the traveling device is set in motion. This, of course, drives the cutter 4 75 through the aforesaid pinions and these pinions are so proportioned as to transmit to said cutter a relatively high speed.

The feeding mechanism for the sealing strip, which is also driven from the shaft 30 30, will now be described. It includes a suitable guide 32 having spaced walls to receive the sealing strip therebetween and openings therethrough to receive gripping and feeding rolls for said strip. One set 35 of rolls is arranged contiguous to the receiving end of the guide and includes a fixed roll 33 and a yielding roll 34, the latter being mounted upon a short lever 35 biased by a spring 36 to press said roll 34 against said 90 roll 33. The other set includes similar rolls 37 and 38 located adjacent to the delivery end of said guide. Thus the rolls 33 and 34 grip the sealing strip as it enters the guide and feed the same to the rolls 37 and 38, 95 which in turn feed the strip through the delivery end of the guide. The rolls 33 and 37 are power operated in the following manner: The roll 33 has fixed thereto a pinion 39, connected through a pinion 40, to a pinion 41 on the aforesaid shaft 30. This provides for positive drive of the roll 33 which in turn drives the roll 37 through a train of pinions 42 including a pinion fixed to said roll 37. Thus, like the rotary cutter, 105 the feeding mechanism is set in operation upon movement of the traveling device. However, it is only desired to have the feeding mechanism operate during movement of the traveling device in one direction and accordingly means are preferably provided for rendering the feeding mechanism inoperative during reverse movement of the traveling device. The means illustrated for this purpose comprises a roller clutch 44 interposed between the pinion 41 and the shaft 30, said clutch operating in a well-known manner to connect and release said parts according to the direction of rotation of said shaft. It should, of course, be understood 110 that various other means might be employed for the aforesaid purpose.

Next considering the knife for severing the sealing strip, the same is illustrated as reciprocably working in a block 45 abutting the end of the guide of the feeding mechanism and having a passage 46 therethrough forming in effect a continuation of said guide. The knife may, in practice, be operated in any preferred way, but as illus- 125
130

trated the same is connected by a rod 47 to the plunger of a solenoid 48, suitably mounted on the traveling device. The solenoid 48 when energized forces the knife downwardly 5 to sever the sealing strip while a spring device 49 is provided to retract the solenoid plunger and thus raise the knife when the solenoid is deenergized.

The pressure device 7 is preferably arranged in close proximity to the knife block 10 so as to ride onto the sealing strip immediately after the same emerges from said block. This pressure device is preferably detachably secured to the traveling device 15 and provided with a more or less free connection therewith, whereby its full force will be exerted upon the sealing strip and webs. To this end the same is preferably provided with laterally projecting pins 50 and 51 fitting 20 into notches 52 and 53 respectively in opposite sides of the traveling frame. Also, in practice, the pressure device is preferably electrically heated as by a coil 54 diagrammatically illustrated in Fig. 4.

As will now be apparent when the traveling device is moved forwardly the rotary cutter will be set in operation and the feeding mechanism will likewise be set in operation to unreel the sealing strip and feed the same to a point just in advance of the pressure device which during continued movement rides over said strip, heating and pressing the same against the webs. Then to sever the sealing strip after completion of 35 the sealing operation it is merely necessary to energize the solenoid 48 to operate the knife 22 as aforesaid.

The propulsion of the traveling device to effect the aforesaid operations is accomplished by the motor as follows: Referring to Fig. 5 the motor has fixed to its armature shaft a pinion 55 which meshes with a gear 56 fixed to a shaft 57 on which shaft is also fixed a pinion 58 meshing with a 45 gear 58^a fixed to the roller supporting shaft 19. The shaft 19 in turn has fixed to one end thereof a pinion 59 which, like the pinion 31, is adapted to mesh with a stationary rack on the table frame. Thus when 50 the motor is set in operation it drives the pinion 59 through the gearing aforesaid to positively propel the traveling device along the table frame at the desired speed, it being understood that the intermediate gearing 55 may be designed for any preferred speed and that the motor is reversible to propel the device in either direction.

Adverting now to the frame 11 which supports the traveling device, the same is preferably constructed as follows: As best illustrated in Figs. 3 and 7, it is provided with two parallel bars 60 and 61 disposed on opposite sides of the slot 2 in the table. These bars, as shown in Fig. 7, are of channel iron construction and are provided on

their upper sides with rails 62 and 63 for the supporting rollers of the traveling device. Also, the bar 60 is provided on its upper side with a rack bar 64 furnishing the aforesaid fixed rack for the pinions 31 and 59 of the traveling device. Thus is provided a fixed path of movement for the traveling device coincident with the slot 2 in the table which slot as above stated is provided to receive the rotary cutter 4 of said traveling device.

The frame 11 also, as previously stated, carries the clamping strips 3 of Fig. 2 and as shown in Fig. 7 these strips are suitably attached to the undersides of the bars 60 and 61. In practice, these strips preferably comprise lengths of rubber tubing, this material being selected for its yielding and gripping qualities. However, other material might be used therefor, if desired. 85 Also, in practice, the clamping strips are preferably arranged in as close proximity to the groove 2 as the construction of the traveling device will permit so as to grip the webs as near as possible to the line of 90 severance and thereby reduce the liability of the cutter snagging the edges of the webs. For this, the bar 60 is shown as provided with an inward extension 65 for carrying its respective clamping strip 3. In 95 some instances, also, one of the bars may be advantageously provided with spring fingers 66 to bear upon the webs and thus supplement the gripping action of the rubber strips. Thus provision is made for firmly 100 clamping the webs against the table and thereby firmly securing the same in position for cutting and splicing.

In addition to clamping the webs against the table, it is desirable to provide means 105 for marginally spacing the webs to receive the point of the plow 5 on the traveling device therebetween. In practice, such marginal spacing of the webs may be accomplished by various means, as, for example, 110 that illustrated in Fig. 8. In this figure the table is illustrated as provided with a finger 67 suitably arranged between the bars of the table frame 11 so that one web may be passed beneath and the other over the same 115 as indicated by dotted lines. For simplicity of illustration the finger 67 is shown in fixed position, although it should be understood that the same might be pivoted, and provided with a suitable operating member 120 whereby it may be raised similarly to the table frame for enabling positioning of the under web and then lowered prior to positioning of the upper web. Also, it should be understood that the two webs might be 125 manually spaced for initial insertion of the plow therebetween.

The provision of an electric motor for propelling the carriage and of a solenoid for operating the knife 22 obviously adapts the 130

mechanism for electrical control in any one of a number of different ways. For such control the circuit connections for the electric parts on the movable carriage may be 5 readily provided for by the means illustrated in Fig. 7. This means comprises a plurality of contact strips 68 mounted on an insulating block 69 fixed to the bar 60 of the table frame, and coöperating contact 10 brushes 70 mounted upon an insulating block 71 adapted to be secured to the traveling device. It is, of course, to be understood that the number of contact strips and brushes may be varied, as desired.

15 One very advantageous form of control for the mechanism described is disclosed in the Reisbach application, aforesaid.

What I claim as new and desire to secure by Letters Patent is:—

20 1. In a machine for uniting material of the character described, in combination, a supporting table for the material and a unitary cutting and sealing device for the material movable across said table.

25 2. In a machine for uniting material of the character set forth, in combination, a table for supporting the adjacent ends of the material to be united, and a device movable across said table and provided with 30 means for automatically cutting and sealing the material as it is so moved.

35 3. In a machine for uniting material of the character set forth, in combination, a table for supporting the material and a device mounted for movement across said table and provided with means operating upon movement thereof to progressively trim the material, displace the waste thereof and secure the parts together.

40 4. In a machine for uniting paper or the like, in combination, a work supporting table and a device mounted for movement across said table, said device carrying a supply of sealing material and having 45 means operating upon its movement to trim the paper and other means to automatically apply said sealing material to the paper as the trimming thereof progresses.

5. In a machine for cutting material of 50 the character set forth, in combination, a table for supporting the ends of a plurality of pieces of material in an overlapped relation, a cutting device movable across said table for severing the overlapping portions 55 of the material and means fixed to said device for displacing the severed end of the upper piece of material.

6. In a machine for cutting material of the character set forth, in combination, a 60 table for supporting the ends of a plurality of pieces of material in an overlapped relation and having means for clamping the material thereto in such relation and a device movable across said table, said device hav-

ing means for severing the overlapped pieces 65 on a common line and means for displacing the end portion of the upper piece as severed.

7. In a machine for cutting material of the character set forth, in combination, a 70 table to support two pieces of material in an overlapped relation, a device movable across said table to sever the overlapping portions of the material and having a member adapted to enter between the two pieces 75 to displace the waste of one of the same and means associated with said table to marginally space the pieces of material to admit said members therebetween.

8. In a machine for cutting material of 80 the character set forth, in combination, a table for supporting two pieces of material in an overlapped relation, and a device movable across said table for severing the overlapping portions of the material, said 85 device having a fixed line of movement obliquely disposed to the material.

9. In a machine of the character set forth, in combination, a work table and a device 90 mounted for movement across said table, said device being provided with a cutter, a waste displacing member, a supply of sealing material and feeding and applying means for said sealing material.

10. In a machine of the character set 95 forth, in combination, a work table, and a unitary mechanism mounted for movement across said table and including a cutter, a waste displacing member, a reel of sealing strip, a feeding mechanism for said strip; and a pressure device for applying said strip to the work.

11. In a machine of the character set forth, in combination, a work table, and a device mounted for movement across said 105 table and provided with a reel of sealing strip, a feeding mechanism for said strip and a pressure attachment for applying said strip to the work.

12. In a machine of the character set 110 forth, in combination, a work table, and a device mounted for movement across said table and provided with a reel of sealing strip, a feeding mechanism for said strip, a pressure attachment for applying said strip 115 to the work and a cutter for said strip disposed between said feeding mechanism and said pressure device.

13. In a machine of the character set 120 forth, in combination, a work table and a device mounted for movement across said table and provided with a reel of sealing strip, a feeding mechanism for said strip and a heated pressure member for applying said strip to the work.

14. In a machine of the character set 125 forth, in combination, a work table, a frame mounted on said table to be raised and low-

ered with respect thereto, and a cutting and sealing device mounted on said frame to travel across said table.

15. In a machine of the character set forth, in combination, a work table, a frame mounted on said table to be raised and lowered with respect thereto, and a cutting and sealing device mounted on said frame to travel across said table, said frame when lowered serving to clamp the work against said table.

16. In a machine of the character set forth, in combination, a work table, a movable frame extending across said table transversely of the work and adapted to be raised and lowered with respect to said table and a cutting and sealing machine mounted on said frame and having a path of movement on a bias with respect to the

20 work.

17. In a machine of the character set forth, in combination, a work table, a frame extending across the same and fulcrumed adjacent to one side thereof, said frame be-

ing thereby movable toward and away from 25 said table and having resilient parts coöperating with said table as a work clamp, and a device mounted to travel on said frame, said device being movable into and out of operative relation with the work by move- 30 ment of said frame.

18. In a machine of the character set forth, in combination, a work table, a frame associated therewith and movable toward and away from the same and a cutting de- 35 vice mounted for movement on said frame, said frame when lowered to said table acting to clamp the work against said table at points on opposite sides of the line of movement of said cutting device. 40

In witness whereof, I have hereunto subscribed my name in the presence of two witnesses.

GLENN S. WILLIAMSON.
